CLAIM

The ornamental design for a powered drill, as shown and described.

DESCRIPTION

FIG. 1 is a top view of the powered drill of the present invention;

FIG. 2 is a bottom view of the powered drill of the present invention;

FIG. 3 is a front view of the powered drill of the present invention;

FIG. 4 is a rear view of the powered drill of the present invention;

FIG. 5 is a left view of the powered drill of the present invention;

FIG. 6 is a right view of the powered drill of the present invention;

FIG. 7 is a perspective right view of the powered drill of the present invention; and,

FIG. 8 is a perspective left view of the powered drill of the present invention.

1 Claim, 8 Drawing Sheets
